UNITED STATES PATENT OFFICE.

CHARLES J. RAMSTEAD AND PETER J. JOHNSON, OF OURAY, COLORADO.

MINER'S CANDLESTICK.

No. 922,950.

Specification of Letters Patent.

Patented May 25, 1909.

Application filed October 13, 1908. Serial No. 457,484.

To all whom it may concern:

Be it known that we, CHARLES J. RAMSTEAD and PETER J. JOHNSON, both citizens of the United States, and residents of Ouray, 5 in the county of Ouray and State of Colorado, have invented a new and Improved Miner's Candlestick, of which the following is a full, clear, and exact description.

Our invention relates to candlesticks, and 10 more particularly such as are adapted for use in mines or other similar places, and each of which in general consists of an elongated body member adapted to have one end driven into the wall of a mine, a folding 15 hanger pivotally secured on the body member and a bracket for holding a candle in place.

The object of our invention is to provide 20 a device of the class described, simple and serviceable in construction and inexpensive to manufacture, which is of convenient size so that it can be carried on the person of the user, and thus be ready for immediate use.

Reference is to be had to the accompanying 25 drawings forming a part of this specification, in which similar characters of reference indicate corresponding parts in all the views.

Figure 1 is a perspective view of an embodiment of our invention; Fig. 2 is an inverted plan view having a part broken away; 30 Fig. 3 is a side elevation showing the hanger being raised into a vertical position, and Fig. 4 is a similar view showing the hanger in the vertical position.

35 In the specific form shown in the drawings, we provide an elongated body member 1, formed of any suitable metal such as iron, steel or the like. This member has one end tapered to form a spike 2, the latter being adapted to be driven into the wall of a mine. The other end of the body member 40 is bent upon itself to form a loop 3, its extremity 4 being offset and laterally disposed, as shown most clearly in Figs. 1 and 2. In 45 the preferred form shown, the offset portion 4 is suitably formed to constitute a socket 5, the latter being adapted to receive a candle or other light-giving element. Further, we do not limit ourselves to the necessity of 50 having the socket integral with the offset portion, as the socket could be formed of a separate strip of metal attached to the offset portion in any suitable manner. The socket further has a certain amount of resiliency 55 so that it will hold a candle firmly in place.

Arranged on the body member 1 is a

bracket 6, which pivotally supports a hanger 7 in place, the latter having its end 8 formed to constitute a hook. This hanger serves to support the body member should it be undesirable to drive the sharpened end or spike 2 of the latter into the wall of the mine. The lower end 9 of the hanger is cut-away to form a finger, as shown most clearly in Fig. 1. The portion 10 of the body member, which lies 60 adjacent to the latter, is provided with a recess 11. It should be understood that there is a certain amount of resiliency in the end 3 and the portion 10, so that the latter, when forced away from the body member by pressure against either the socket 5 or the offset portion 4, will tend to return to its normal position. Therefore, when it is desired to move the hanger 7 into an operative or vertical position, the lower end 9 will engage at 70 the portion 10 of the body member to force it out of position until the end of the hanger has been received in the recess 11, where it is firmly held in position until an outward pressure has been brought to bear at either 75 the socket or the offset portion, to release the end of the hanger from the recess.

The eye formed at one end of the body member allows the device to be hung from a hook or other projection when it is not in 80 use. It also serves for hanging the candle stick upon the person of the user, and affords means for conveniently carrying it.

It will be understood that while the device is particularly useful in mines, it can also be 85 advantageously employed wherever a simple candle stick is desirable, and which can be either hung in an operative or inoperative position, or can be forced into a wall or other support.

Having thus described our invention, we 90 claim as new and desire to secure by Letters Patent:

1. In a device of the class described, an elongated body member having one end 100 sharpened and having the other end bent upon itself to form a loop, said looped end having the extremity adjacent to said body member and carrying a socket adapted to receive a candle, said extremity having a recess, a bracket upon said body member, and a hanger pivoted at said bracket and having a finger adapted to be forced between said body member and said extremity to engage said recess whereby said hanger is held in an 105 operative position.

2. A device of the class described com-

prising a closed loop one of whose arms is extended beyond the other and sharpened for the purpose set forth, the other arm lying alongside the first named arm and having at 5 the extremity thereof a socket, and a hanger pivoted on the first named arm, and having an extended end engaging between the arms of the loop when the hanger is turned at right angles thereto.

In testimony whereof we have signed our 10 names to this specification in the presence of two subscribing witnesses.

CHARLES J. RAMSTEAD.
PETER J. JOHNSON.
